(57) **CLAIM**

The ornamental design for a finger mounted toothbrush, as
shown and described.

DESCRIPTION

FIG. 1 is a front perspective view of the finger mounted
toothbrush of our new design, as seen from the bottom, right
side thereof;

FIG. 2 is a top elevation view thereof;

FIG. 3 is a bottom plan view thereof;

FIG. 4 is a right side elevation view thereof, the left side
elevation view being a mirror image of this right side plan
view as shown in this FIG. 4;

FIG. 5 is a front elevation view thereof; and,

FIG. 6 is a rear elevation view thereof.
